UNITED STATES PATENT OFFICE.

EDWARD S. RENWICK, OF MILLBURN, NEW JERSEY.

THERMOSTAT FOR INCUBATORS.

SPECIFICATION forming part of Letters Patent No. 281,397, dated July 17, 1883.

Application filed September 4, 1882. (No model.)

To all whom it may concern:

Be it known that I, EDWARD SABINE RENWICK, of Millburn, in the county of Essex and State of New Jersey, have made an invention of certain new and useful Improvements in Incubators; and I do hereby declare that the following, taken in connection with the accompanying drawings, is a full, clear, and exact description and specification of the same.

10 The object of the present improvement is to simplify the construction of incubators and improve their operation; and to these ends the invention consists of certain new and useful combinations of devices which are recited in the claims at the close of this specification. The said combinations are described and were claimed in a specification made by me and dated the 11th day of January, A. D. 1882; but as the Commissioner of Patents has decided that these combinations could not be embraced in the same patent with other combinations which formed parts of my complete incubator, the former are claimed under this division of my invention, while the claims to 15 the latter are retained in another division of my invention. In order that these combinations may be understood, I have represented in the accompanying drawings, and will proceed to describe, the best mode in which I have embodied the same for practical use, it being understood that the mode of embodying the improvements may be modified as circumstances or the views of different constructors may render expedient.

20 Figure 1 of said drawings represents a front view of the incubator. Fig. 2 represents an end view of the same. Fig. 3 represents a plan of the same. Fig. 4 represents a transverse section of the incubator at the line $x x$ of Fig. 3. Fig. 5 represents a central longitudinal section of the same. Fig. 6 represents a horizontal section of the incubator at the line $y y$ of Fig. 5. Fig. 7 represents a similar section above the tops of the egg-holders 25 or trays for eggs, and Fig. 9 is a plan of the heat-distributer. Figs. 10 to 17, inclusive, represent views of various portions of the incubator—Figs. 10 to 13 and 15 to 17 of half the working dimensions, and Fig. 14 being of 30 full size.

The incubator represented in the said draw-

ings embodies improvements recited in previous patents granted to me, as well as those recited in the claims at the close of this specification, A A' being the incubating-chamber; 55 B B', the egg-holders in the form of drawers, (fitted either with rollers or with perforated bottoms;) d, the heat-flues; I, the waste-heat chimneys; E E, the chimney-valves; G, the ventilating-chimney; K, the ventilating-valve; J J, 60 the air-supply pipes; M M, the water-trays, open at their tops; N N, the water-fountains; Q Q, the water-basins, connected with the water-trays by tubes; and e e', the horizontal portions of the flues. As all the said parts of the incubator represented in the drawings are fully described in the said previous specification, dated January 11, A. D. 1882, it is not deemed necessary to describe them minutely herein.

The egg-holders B B' are arranged in pairs, 70 back to back, with their backs separated by a space which is wide enough to receive the thermostat S, which is placed between the egg-holders, so that it is at the level of the egg-holders, or thereabout, and is affected by substantially the same changes of heat that affects the eggs in the egg-holders, thus causing the thermostat to be a more reliable indicator of such changes than it is when placed in the top 75 of the incubating-chamber or in a separate 80 compartment connected with that chamber.

According to the present invention the thermostat is constructed to operate by its tensile force. It is composed of a tensile strip of vulcanite (hard rubber) sustained by a frame. 85 The expansive tensile strip of vulcanite s in the incubator represented in the drawings is about thirty-nine inches long. Its frame (see more particularly Figs. 13, 14, 16, and 17) is made by preference of two bars, t t, of dry 90 wood, connected together by metallic mountings u u. Each end of the frame carries a lever. The lever V, at one end of the frame, is forked at its upper end to receive one end of the vulcanite strip s, and is pivoted at its lower 95 end to the metal mounting u. At an intermediate part of this lever there is a swiveling nut, w, to which the adjusting-screw W is fitted, so that the lever V becomes an adjusting-lever, by which the expansive tensile strip may 100 be adjusted longitudinally for use. The stem of said screw W is long enough to pass through

a hole in the adjacent end wall, a' , (of Fig. 5,) of the incubator, so that the head of the adjusting-screw is at the exterior, where it may be conveniently turned without the necessity of opening the incubator. The lever V' , at the opposite end of the incubator and frame, is used to transmit the motion by expansion and contraction of the expansile strip to the device to be controlled by it. This motion-transmitting lever V' is of elbow form, is pivoted to the adjacent metal mounting, and is connected at its vibrating end with a second lever, V^2 , by means of a link, v . The end of the second lever, V^2 , is connected by a rod, l , with the detent-lever W' of the valve-engine above, (see Fig. 15,) and the rock-shaft x of this detent-lever is fitted with a weighted arm, U , (which, if deemed best, may be replaced by a spring.) The strip of vulcanite is connected with the levers V V' of the thermostat by pivots, and the levers, links, and rods are also connected by pivots. The levers are arranged, as represented in the drawings, (or in some other equivalent mode,) so that the expansile strip of vulcanite is subjected to the tensile strain of the weight U , whose force is multiplied by the action of the levers. Consequently the expansile strip of vulcanite s is constantly under a strong tensile strain far greater than the force it is required to exert to move the detent I' . Moreover, as the weight U is at one end of the system of connections with the detent I' , Figs. 13 and 15, of the valve-engine, while the expansile strip s is at the other end of the same system, and the two operate antagonistically, all the play of the connections is taken up, and the thermostat operates with great certainty and force. The holding of the expansile strip under a tensile strain between two levers, V V' , enables one of them to be used with advantage to adjust the position of the strip longitudinally, as required, so that it may be set to operate the detent when the temperature is at the desired degree, while the other lever (at the opposite end of the said strip) transmits movement to the detent, multiplied in extent. This mode of holding the strip also incidentally permits the strip to be arranged above the frame upon which it is strained, so that it is exposed at both sides to the action of the heat of the atmosphere.

The dynamic or valve engine has preferably but one revolving shaft, N' , which is fitted with a chain-wheel, O , and two detent-arms, S' S^2 . These arms operate in connection with the detent I' , each arm having a cross end, s' , fitted to pass through the slot of the detent when the slot is moved to the proper position by the action of the thermostat S . One of the arms is longer than the other, so that their ends are at different radial distances from the axis of the main shaft N' . Consequently, when the detent is moved to a position to permit one arm, S^2 , to escape through the detent-slot i , Fig. 15^a, the face of the detent is in position to stop the other arm, S' , when the engine-shaft N' has made half of a revolution. The chain-

wheel O receives the chain of the weight O' , Figs. 1 and 2, by which the requisite power to move the valves is supplied; and it is expedient to apply a ratchet-wheel, R' , to the engine-shaft N' , with a pawl upon the engine-frame, to prevent the accidental backward movement of the engine-shaft. The engine-shaft N' is fitted with a crank, whose crank-pin is connected by a rod, P^2 , Fig. 5, with the arm c' of the valve rock-shaft D , whose ends are fitted to rock in bearings in the heads of the standards b' b' . The rock-shaft D' carries the arms b^2 b^2 , Figs. 2 and 3, from the ends of which the valves E , which control the waste-heat chimneys I I , are suspended, the valves being raised to open these chimneys and permit the heat from the lamps to escape when the heat of the incubating-chamber rises, and being dropped to close the waste-heat chimneys when the heat in the incubating-chamber falls below the mean temperature. The same valve rock-shaft is connected by an arm, b^3 , a rod, m' , (passing through a hole in the wall of the ventilating-chimney,) an elbow-lever, b^4 , with the ventilating-valve K , so that the valve is raised or opened and is dropped or closed simultaneously with the opening and closing of the chimney-valves E E .

A liquid speed-controller is employed to prevent the engine-shaft N from moving with too great speed. In a previous patent I have described such a controller as made separately from the engine, but combined with it. In the present case the paddle-arms y' of the paddles y of the speed-controller are connected directly with the engine-shaft at about the center of the engine-frame, and the trough F (shown in dotted lines in Fig. 15) of the controller is secured to the cross-bars n' n' of the said frame, so that the members of the liquid speed-controller are held in the proper relationship by the engine-frame.

The weight-chain M' and weights O' O^2 are arranged, by preference, according to the Huyghens system, the chain M' being continuous and being applied to the pulleys d' d' (see Fig. 1) of two weights, O' O^2 , of which one, O^2 , is lighter than the other, O' , by being made hollow, and the shaft of the counter chain-wheel O^3 , Figs. 1 and 2, being fitted with a ratchet-wheel controlled by a pawl, (or a pawl being fitted to operate directly upon the chain-wheel,) so that the power-weight O' may be wound up by turning counter chain-wheel O^3 without affecting the engine. It is also expedient to connect the two weights by a chain, M^2 , of double the lineal weight of the main chain M' , so that the strain upon the engine is not varied by changes in the position of the weights. It is also expedient to cover the valve-engine with a glass shade, R^2 , to protect it from dust.

Under this division of my improvements, I claim as my invention—

1. The combination, substantially as before set forth, of the straight expansile strip of the thermostat, the lever and weight arranged to

act upon one end thereof, and the adjusting lever and screw at the opposite end thereof.

2. The combination, substantially as before set forth, of the expansile strip of the thermostat and the frame thereof with a weight by which the said strip is subjected to a strong tensile strain.

3. The combination, substantially as before set forth, of the thermostat, the detent moved thereby, the revolving shaft carrying the detent-arms, the paddle-arms, also carried by said shaft, the trough through which said paddle-arms move, and the engine-frame holding the said detent-shaft, detent-arms, paddle-arms, and trough in their proper relative positions.

4. The combination, substantially as before set forth, of the walls of the incubator, the expansile strip of the thermostat inclosed therein, the weight operating upon one end of said strip to subject it to a tensile strain, and the adjusting-screw which operates upon the other end of said strip and extends through the adjacent wall of the incubator.

In witness whereof I have hereto set my hand this 29th day of August, A. D. 1882.

EDWARD SABINE RENWICK.
